Application January 3, 1944, Serial No. 112,156

Term of patent 14 years

(CL. D71—1)

To all whom it may concern:

Be it known that we, Walter A. Hite, residing at Palos Verdes Estates, in the county of Los Angeles, State of California; Richard E. Harvuot, residing at Inglewood, in the county of Los Angeles, State of California; and David H. Williams, residing at Los Angeles, in the county of Los Angeles, State of California, all citizens of the United States, have invented a new, original, and ornamental Design for an Airplane, of which the following is a specification, reference being had to the accompanying drawings, forming part thereof.

In the drawings

Fig. 1 is a perspective view of an airplane showing our design;

Fig. 2 is a top plan view of the airplane;

Fig. 3 is a side elevational view of the airplane;

Fig. 4 is an inverted plan view of the airplane; and

Fig. 5 is a front elevational view thereof.

We claim:

The ornamental design for an airplane, as shown.

WALTER A. HITE,
RICHARD E. HARVUOT,
DAVID H. WILLIAMS.
